UNITED STATES PATENT OFFICE

SAMUEL E. SPERRY, OF HOLLIS, NEW YORK, ASSIGNOR TO INTERTYPE CORPORATION,
OF NEW YORK, N. Y., A CORPORATION OF NEW YORK

MATRIX-ALIGNING MEANS

Application filed March 8, 1929. Serial No. 345,528.

The present invention relates to improvements in typographical machines and more particularly to those of the well known class using character bearing matrices which are drawn from a magazine under the control of a keyboard and are assembled in a line from which a type bar or slug is cast, a machine of this general class being shown and described in U. S. Letters Patent No. 436,532 granted September 16, 1890, to O. Mergenthaler.

Machines of this class have been developed so that they are adapted to use either matrices each having a single type forming character punched therein or matrices each bearing two of such characters located at different heights, such machines having an assembling elevator, a delivery channel, a first elevator and a casting mold, each of such parts being provided with rails for supporting the matrices during their advance through the machine and for aligning them in front of the mold for the purpose of casting the type bar or slug against a line of such assembled matrices.

The usual two-letter matrices as heretofore generally used have two type forming characters punched in their casting edge in such position with respect to the usual upper and lower lugs on that edge of the matrix as to permit one or the other of the characters to align with the slug casting cavity of the mold while the portion of the casting edge of the matrix which lies between the character punchings engages the face of the mold and forms a seal which prevents flow of the molten type metal beyond the character punching which is aligned with the mold and from which the cast is to be made. Heretofore, the character punchings in two-letter

matrices have been spaced apart a predetermined distance and the machines have been constructed accordingly to use such matrices, but the alignments heretofore used for the upper and lower character punchings in two-letter matrices and the corresponding construction of the machine to conform with such matrices have limited the point size of the characters which it is possible to use in the matrices although a demand has arisen

for the casting of type bars or slugs having larger point sizes.

The primary object of the present invention is to provide certain improvements whereby standard machines of the general class hereinbefore referred to may be adapted to properly align two-letter matrices irrespective of whether the character punchings thereon are located on the usual alignments heretofore generally used or are located on alignments which are spaced apart to a greater extent than heretofore and have character punchings of larger point sizes than heretofore possible with two-letter matrices heretofore used and which require an extra high alignment.

A further object of the invention is to provide means for controlling the aligning of the matrices with respect to the mold so that matrices either of the usual two-letter kind or those requiring an extra high alignment may be properly positioned with respect to the slug casting cavity in the mold, such means preferably comprising a transport rail which supports the matrices while they are being advanced to the extra high alignment, the mere setting of such rail adapting the machine to the casting of slugs from one or the other form of matrices, thereby avoiding the necessity of applying to the machine special parts with special matrix aligning means whenever matrices of one or the other form is to be used in the machines.

To these and other ends, the invention consists in certain improvements and combinations and arrangements of parts, all as will be hereinafter more fully described, the features of novelty being pointed out particularly in the claim at the end of the specification.

In the accompanying drawings:—

Fig. 1 is a perspective view of a two-letter matrix of the usual form commonly used heretofore in typographical machines of the class to which the present invention is directed;

Fig. 2 is a perspective view of a two-letter matrix of improved form wherein the space between the upper and lower character alignments has been increased and the point size of the character punchings increased;

Fig. 3 represents a vertical transverse section taken through the mold and the first elevator or matrix positioning means of a typographical machine, showing in full and dotted lines respectively a matrix like that shown in Fig. 1, positioned at the usual low and high alignments with respect to the mold;

Fig. 4 is a view similar to Fig. 3 but showing the mold and the first elevator modified and adapted to receive matrices of the improved kind such as shown in Fig. 2, the full and dotted lines showing respectively such a matrix positioned at the low and extra high alignments with respect to the mold;

Fig. 5 represents a transverse vertical section through the mold and the first elevator of a typographical machine showing a single letter matrix having a character punching of maximum size heretofore possible aligned in front of the mold;

Fig. 6 is a view similar to Fig. 5 but it shows the mold and first elevator modified to align a single letter matrix having a character of relatively larger point size in front of the mold;

Fig. 7 is an end view, partly in section, of the matrix delivery channel through which the matrices pass on their way to the first elevator, the delivery channel being modified to control the placing of the usual two-letter matrices at the usual high alignment and the placing of the improved matrices at the extra high alignment; and

35 Fig. 8 represents a section taken longitudinally through the delivery channel on the line 8-8 of Fig. 7 and looking in the direction of the arrows, a portion of the first elevator being shown in position to receive the
40 matrices from the delivery channel.

Similar parts are designated by the same reference characters in the several figures.

In typographical machines of the general class shown in the patent hereinbefore described as heretofore constructed to use two-letter matrices, the matrices were constructed substantially as shown in Fig. 1 wherein M represents the matrix generally, it having upper and lower lugs or ears E and E' and having upper and lower type forming characters C and C' respectively punched or otherwise formed in the rear or casting edge of the matrix which, in machines of this class, is brought into position against the front of the mold, it being understood that the type forming characters are formed in the casting edge of the matrix in the space between the upper and lower ears E and E' at that edge of the matrix. The mold which, in machines of this class is carried by a mold wheel, as is generally understood by those familiar with machines of this class, usually comprises a mold body 1 and the mold cap 2, the mold body and cap being mounted usually in fixed relation to one another and

spaced apart or otherwise formed to provide a cavity 3 between them in which a type bar or slug is adapted to be cast by the injection of molten metal into this cavity from its rear side, from the mouthpiece of a metal pot which is brought into contact with the rear face of the mold at the appropriate time and while a matrix line is presented to the front of the mold so that the type forming characters therein are aligned with the mold cavity, the portions of the casting edge of the matrices above and below the type character aligned with the mold cavity contacting with the front faces of the mold cap and mold body respectively and forming metal tight joints which prevent escape of the molten metal beyond the character bearing portions of the matrices. The matrix line, in machines of this class, is brought to casting position in front of the mold by a so-called "first elevator" which comprises front and rear jaws 4 and 5 which are spaced apart and form a channel 6 between them into which the matrix line is introduced by endwise movement through a so-called delivery channel preparatory to the casting operation, after which the matrix line is removed from the elevator by a reverse endwise movement into a transfer channel from which the matrices are transferred to the distributor of the machine for return to their respective channels in the magazine. In machines of this class as heretofore constructed to use two-letter matrices as heretofore constructed, the rear face of the front jaw 4 of the elevator has been provided with an aligning bar 7 fixed at the appropriate level on said jaw so that its upper edge will provide a supporting and aligning surface for the upper lug or ear E on the front edge of the matrix and its lower edge will provide an aligning surface for the lower lugs or ears E' on the forward edges of the matrices which occupy the high alignment position which will present the lower character C' to the casting cavity in the mold, and a so-called duplex rail 8 has been usually fitted into the front jaw of the elevator, this rail having a single groove or recess at its rear edge to provide a surface 9 on which the lower lugs or ears E' at the front edge of the matrices assembled in the high alignment position may rest and thus be supported in that position, the lower edge of the duplex rail forming an aligning surface against which the lower lugs or ears E' of the matrices assembled at the lower level may align. This duplex rail 8 is mounted movably in the front jaw of the first elevator so that it projects into the matrix channel as shown in Fig. 3 when the matrix line is introduced therein and it is retracted, after the casting operation has been completed, to permit all of the matrices to come to common alignment at the lower level where their upper front ears rest on the top of the aligning bar 10

ing rail 7, as for example is illustrated and described in U. S. Letters Patent No. 1,108,829, granted August 25, 1914, to W. E. Bertram. The rear jaw 5 of the first elevator, as heretofore constructed, has been customarily provided with a rail 10 at its lower edge to overlie the front portion of the mold cap 2 and to underlie and support the upper lugs or ears E on the rear or casting edge of the matrices assembled on the lower casting level, it being clear from Fig. 3 of the drawing that sufficient space was required between the top of the mold cap and the upper lugs or ears of the matrices occupying the lower casting level to accommodate the rail 10 between these parts. Also, in machines of this general class as heretofore constructed to use two-letter matrices of the form heretofore used generally, the front face of the mold body 1 has been grooved to form upper and lower aligning rails 11 and 12 which were on the same levels with the lower edge of the aligning rail 7 and the lower edge of the duplex rail 8 respectively, the aligning rails 11 and 12 in consequence being spaced closely, one above the other.

In two-letter matrices as heretofore constructed for use in machines of this general class, the constant alignment line of the upper character has been located at the level indicated by the line $a-a$ and the constant alignment line for the lower character has been located at the level indicated by the line $a'-a'$, Fig. 1, the maximum point size of the characters being limited, usually to 18 points, because of the space required on the casting edge of the matrix above the upper character C for the accommodation of the forward edge of the mold cap and the rail 10 on the rear jaw of the elevator, this limiting the size of the upper character and the necessity of leaving a portion of the casting edge on the matrix to intervene the upper and lower characters C and C' to form a metal seal or joint with the front face of the mold correspondingly limiting the size of the lower character.

The present invention provides a matrix bearing type forming characters of greatly increased point size as compared with the maximum size heretofore useable on two-letter matrices, it being positioned to use characters up to 26 point size on matrices which are otherwise of the same form and dimensions as those heretofore used, and it embodies improvements in the machine which adapt it to the casting of type bars or slugs of correspondingly increased point sizes from the improved matrices while at the same time adapting the machine to use matrices of the forms heretofore commonly used.

Fig. 2 of the drawing illustrates the improved matrix designated M' which, as stat-

ed corresponds in form and dimensions to matrices of the kind shown in Fig. 1 except that while the constant alignment level for the upper type forming character C³ is located at the level $a-a$ in Fig. 2 which agrees with the constant alignment level for the upper character C in Fig. 1, the constant alignment level for the lower character C⁴ in Fig. 2 is located at the substantially lower level a^2-a^2 , and the larger upper character C³ extends to a greater height above the line $a-a$ on the casting edge of the matrix and the lower character C⁴ of correspondingly increased size extends from the lowered line a^2-a^2 , a sufficient portion of the casting edge of the matrix being left however between the upper and lower characters to form the required molten metal seal with the front face of the mold. In order to adapt the machine to cast from matrices of the form shown in Fig. 2 and to produce type bars or slugs having correspondingly increased point sizes, the rail 10 of the rear jaw of the first elevator is cut off or omitted so that the lower edge of the rear jaw 5 will be flush with or will not extend below the lower edge of the upper rear lugs or ears E of the matrices occupying the lower level in the first elevator, and since the only part then required to occupy the space between the lower edge of the upper ears or lugs E of the matrices and the mold cavity is the front of the mold cap, the mold cap may be spaced at a greater distance from the mold body to form a mold cavity 3^a which is of substantially increased point size as compared with the mold cavity 3 shown in Fig. 3 which has been the largest heretofore possible using two-letter matrices of the usual form in machines of this class as heretofore constructed. In the construction and arrangement shown in Fig. 4 the upper rear lugs or ears E of the matrices at the lower casting level may rest directly on the front portion of the mold cap 2 when the matrix line is brought into casting position and the reduced height of the casting edge of the matrix above the upper character C³ is sufficient to accommodate the vertical height or thickness of this portion of the mold cap. In order to adapt the matrix aligning means of the machine to the casting of slugs from matrices of the form shown in Fig. 2, the usual aligning bar 7 on the front jaw of the first elevator is replaced by an aligning bar 7' which is of less vertical depth than the aligning bar 7 so that its lower edge will occupy a sufficiently high elevation to form an aligning rail for the lower forward lugs or ears E' on the matrices of the form shown in Fig. 2 when such matrices occupy the extra high alignment level to present the lower character C⁴ therein in proper alignment with the mold cavity 3^a, and the upper aligning rail on the face of the mold body is cor-

respondingly raised as indicated at 11^a in Fig. 4. Also, the usual duplex rail 8 is replaced by a rail 8^a which extends to a greater height than the rail 8 heretofore used, the rail 8^a being grooved at its rear edge to form a rail 8^b which is at such a sufficiently high elevation to support the matrices of the form shown in Fig. 2 at the extra high alignment level by the resting of the lower forward lugs or ears E' of such matrices upon the rail 8^b, as shown by the dotted lines in Fig. 4. The channel in the first elevator between the front and rear jaws thereof is extended upwardly to a greater height than heretofore in order to enable the matrices of the form shown in Fig. 2 to occupy the extra high alignment level, as is shown by dotted lines in Fig. 4. The lower edge of the rail 8^a and the rail 12 on the face of the mold body form aligning surfaces for the lower lugs or ears of the matrices when positioned at the lower casting level as shown by the full lines in Fig. 4.

The present invention not only enables typographical machines of the general class hereinbefore referred to to use matrices of the special form shown in Fig. 2 bearing type forming characters of greater point size than has heretofore been possible with the usual two-letter matrices as shown in Fig. 1, but it also enables such machines to use two-letter matrices of the usual form shown in Fig. 1 with equal facility. To accomplish this, the rail 8^a is formed at its rear face not only with the rail 8^b to cooperate with the lower forward lugs or ears of the special matrices as shown in Fig. 2 occupying the extra high alignment level but it is grooved longitudinally or otherwise formed at its rear edge to provide a second rail 9^a below the rail 8^b, this rail 9^a being located at the proper height to engage the lower forward lugs or ears of matrices of the usual form as shown in Fig. 1 and to support such matrices at their upper casting level and the rail 8^a is formed above or opposite to the supporting rail 9^a with an aligning rail 9^b which is positioned to engage the lower forward lugs or ears of matrices of the usual two-letter form as shown in Fig. 1 and to align such matrices at their upper casting level. The lower rear lugs or ears of matrices of the usual form when aligned at their upper casting level are accommodated in the increased space formed between the lower aligning rail 12 and the aligning rail 11^a on the face of the mold body. It will therefore be observed that the improved duplex rail 8^a embodies double aligning rails, that is, the aligning rail formed by its lower edge for the lower forward lugs or ears E' of the matrices when positioned at the lower casting level and the aligning rail 9^b which cooperates with said lugs or ears of matrices of the usual form shown in Fig. 1 when positioned at the usual upper casting level. It will be understood that in the improved construction

of the machine shown in Fig. 4 both the usual form of two-letter matrices as shown in Fig. 1 and the special two-letter matrices as shown in Fig. 2 are aligned at the same lower casting level, but the two-letter matrices of the usual form as shown in Fig. 1 are aligned at their upper casting level by the aligning rail 9^b while the special form of matrix shown in Fig. 2 is aligned at its upper casting level by the aligning surface formed by the lower edge of the aligning bar 7^a, as indicated by the dotted lines in Fig. 4, this extra high alignment of the special matrix conforming with the location of the lower character C⁴ in a lower position on the matrix than heretofore, as has been hereinbefore described. It will be understood that the double duplex rail 8^a is movably mounted in the front jaw of the first elevator so that it may be retracted to bring all of the matrices in the elevator to common alignment preparatory to the removal of the matrix line from the elevator, substantially as shown in Patent No. 1,108,829 hereinbefore referred to.

The present invention provides means for bringing the matrices of special form as shown in Fig. 2 into their extra high alignment level in the elevator and in the preferred embodiment of the invention as herein shown, such means is movable or capable of being set so that it will bring the special matrices to the extra high alignment level when set for such matrices but when it is set for the use of the usual form of two-letter matrices it will permit such matrices to pass into the aligning means or first elevator without affecting them. Preferably and as shown in the present instance, such means comprises a rail 13 which is pivoted at 14 in a recess formed in the rear side of the front wall of the usual delivery channel 16 through which the matrices pass from the assembling elevator to the first elevator. This delivery channel is preferably formed as usual with rails 17 on which the upper lugs or ears E of the matrices assembled at the lower level will rest and over which they will travel, thus supporting such matrices during their travel through the delivery channel and this channel is also preferably provided with rails 18 on which the lower lugs or ears E' of matrices of the usual form shown in Fig. 1 and assembled at their upper casting level may rest and over which they may travel during the movement of the matrix line through the delivery channel, it being understood that the two-letter matrices are commonly assembled at their upper and lower levels, according to the character thereon from which the cast is to be made, by the use of an assembling elevator such for example as that shown and described in Letters Patent 1,149,768, granted Aug. 10, 1915 to T. S. Homans.

The rail 13 provided in the delivery channel operates, when properly set, to raise the

special form of matrices as shown in Fig. 2, assembled at the upper level in the usual assembling elevator, up to the extra high alignment level so that the lower lugs or ears at the 5 forward edges of these special matrices will reach the supporting rail 8^b of the double duplex rail 8^a. The rail 13 is grooved in its rear face to form a rail 19 to receive and support the lower lugs or ears on the front edges 10 of the matrices of special form and to raise such matrices from the usual upper level at which they were assembled up to the extra high aligning level during the passage of such matrices through the delivery channel 15 or into the first elevator. The pivot 14 of the bar 13 is located at that end of the delivery channel which is adjacent to the first elevator and the matrix supporting rail 19 will remain in substantially constant alignment 20 with the matrix supporting rail 8^b of the rail 8^a in the first elevator, but the opposite free end of the bar 13, which is at the entrance or matrix receiving end of the delivery channel, may be swung downwardly so that the 25 rail 19 will receive the lower forward lugs on the special matrices assembled at the usual upper level in the usual assembling elevator, and as these matrices are conveyed through the delivery channel by the usual delivery slide, the special matrices assembled at the 30 higher level will be lifted as they traverse the rail 19 or move toward the left on said rail inclined as shown in Fig. 8 so that they will be raised from the rails 18 and delivered on to the supporting rail 8^b in the first elevator, such matrices then occupying the extra high alignment level represented by the dotted lines in Fig. 4. On the other hand, when the 35 rail 13 is swung upwardly about its pivot 14 so that its rail 19 is parallel to and above the adjacent rail 18 in the delivery slide, the rail 13 will have no effect upon two-letter 40 matrices of the usual form assembled at their higher level while passing through the delivery slide. Any suitable means may be employed for moving or setting the controlling 45 bar 13 either into or out of its operative position, a screw 20 being shown in the present instance for this purpose, its stem extending 50 through a vertically elongated slot 21 formed in the front wall of the delivery channel and its rear end being threaded into the rail 13, the front end of the screw having a knob or head thereon which provides a handle by 55 which the rail may be lifted and lowered, and rotation of the screw in the appropriate direction will clamp the rail 13 in either of its two positions.

60 The present invention also enables single letter matrices having much larger point size characters to be used in machines of this class than has heretofore been possible. Fig. 5 shows a single letter matrix M² of the usual form having in its casting edge the largest point size character m² which it has pre-

viously been possible to use, it being observed that the point size of the mold cavity 3^b is limited by the presence of the rail 10 on the rear jaw of the first elevator and which must be accommodated between the top of the mold cap and the under side of the upper rear lugs or ears E of the matrices. In casting type bars or slugs from single letter matrices forming type forming characters as shown in Fig. 5, the first elevator is stopped, in its descent, at a casting level above its normal level as shown in Figs. 3 and 4, means such for example as that shown by Patent No. 1,439,586, granted Dec. 19, 1922, to M. L. Van Keuren showing elevator stopping means 70 suitable for use for such purpose. However, by omitting or forming the rear elevator jaw 5 without the rail 10, the mold cap 2 may be placed at a higher level above the mold body, as shown in Fig. 6, thus forming a mold cavity 3^b which is of larger point size 75 than the mold cavity 3^b in Fig. 5, it being possible to raise the mold cap to a height where the upper rear lugs or ears E on the matrices rest on the top of the mold cap, 80 and consequently matrices M² having type forming characters m² which extend to a higher point along the casting edge thereof, 85 as will be clear from a comparison of the matrices M² and M³, can be used in the machine, it being possible to use single letter matrices bearing a type forming character 90 as large as 54 points whereas heretofore it has not been possible to employ single letter matrices with type forming characters larger 95 than 46 points.

In the construction shown in Fig. 4 when casts are made from matrices positioned at the low casting level, and in the construction shown in Fig. 6, the mold itself forms the 105 aligning means for both the upper and lower lugs on the casting edges of the matrices, accurate and secure positioning of the matrices with respect to the mold being thereby insured.

110 While it is generally preferable to employ a relatively long rail in the delivery channel in substantially the position shown so that the incline of this rail will extend over a considerable distance and thereby avoid undue steepness in lifting the larger character matrices to the extra high alignment in the matrix retaining jaws of the first elevator, it is to be understood that the lifting of the 115 matrices may be accomplished by other suitable means in the path between the assembling elevator and the first elevator jaws.

120 By omitting or removing the usual rail on the lower edge of the rear jaw of the first elevator, the further advantage of insuring accurate alignment of the matrix line in front of the mold when the matrices are aligned on the lower casting level, as shown by the full lines in Figs. 4 and 6, is secured. Experience has shown that the back jaw of the 130

first elevator sometimes becomes bent out of position by the retraction of the mold after a cast has been made, due to adhesion of escaping type metal to such jaw, and when the back jaw has become so bent or distorted, the rail thereon, as commonly used heretofore, will disturb the alignment of the matrices resting on it, but by omitting or removing this rail, the matrices are then supported by the relatively stronger aligning bar fixed to the relatively massive front jaw, and hence the matrices will be accurately aligned by this aligning bar without disturbance by the rear jaw, although the latter does serve to prevent rearward displacement of the matrices from the aligning bar.

The present invention enables line casting machines of the class now in general use to use matrices of much larger point sizes than has heretofore been possible, by providing the machine with suitable matrix carrying jaws for the larger character matrices that will also align the usual two-letter matrices, without the necessity of exchanging any of the regular parts of the machine, and the usual two-letter matrices and the larger character matrices may be used in separate lines or they may be mixed or assembled in the same line, if such is desired. To use the larger character matrices, it is only necessary to bring the magazine carrying such matrices into operative position in the machine, these matrices being assembled and presented for casting by the usual operation of the machine, although in assembling two-letter matrices bearing the larger characters for casting at the higher casting level, the controlling rail in the delivery channel is set in position to lift these matrices up to the extra high alignment level in the matrix retaining jaws of the first elevator.

I claim as my invention:—

In a line casting machine having elevator jaws for presenting matrices to the mold at a lower and two different upper casting levels, a channel for conducting matrices to said matrix presenting jaws, said channel having relatively fixed rails therein for supporting matrices at the lower level and at the lower of said upper levels, and a supplemental rail movably mounted in said channel to bring its forward end into the path of matrices assembled at the lower of said upper levels and operative to direct such matrices to the relatively higher upper level.

In testimony whereof I have hereunto set my hand.

SAMUEL E. SPERRY.
